UNITED STATES PATENT OFFICE.

WILLIAM L. BJUR, OF NEW YORK, N. Y.

PIANO STRING-PLATE.

No. 847,889.

Specification of Letters Patent.

Patented March 19, 1907.

Application filed October 11, 1906. Serial No. 338,354.

To all whom it may concern:

Be it known that I, WILLIAM L. BJUR, of the city of New York, State of New York, have invented a certain new and useful Improvement in Piano String-Plates, of which the following is a full, clear, and exact specification, such as will enable others skilled in the art to which it appertains to make and use the same.

Early in the history of the manufacture of modern pianos it became the practice to cast the name of the manufacturer into the string-plate of the instrument. In upright pianos, the type to which my invention especially relates, the manufacturer's name was cast in the upper right-hand corner, so that it would be in plain view above the piano-action. This practice has been uniformly followed in the art to the present day. However, it has in recent years become the frequent practice for a manufacturer to construct pianos for a number of commercial houses engaged principally or solely in the business of selling pianos, and since every such house desires its own distinctive name on the string-plates of the pianos handled by it it may be readily seen that the manufacturer to fill orders promptly must carry in stock a great number of string-plates differing only in the name cast thereon, a condition of affairs burdensome to the manufacture in respect to outlay of capital, cost of handling, and expense of storage.

It is therefore the underlying object of my invention to effect some improvement in the piano-manufacturing art by means of which the difficulty referred to above may be overcome. With this end in view I form the string-plate with an oblique upper edge at its right-hand side, which follows approximately the course of the top row of tuning-pins at the right-hand side of the plate. The name-plate I cast or otherwise form separate from the string-plate, and I shape the name-plate with an oblique lower edge running from the right-hand end of the name-plate leftward and upward and meeting the top edge at an acute angle or point. This name-plate is arranged to lap its lower edge over the oblique upper edge of the string-plate and to be bolted to the frame of the piano independently of the string-plate. The name-plate thus arranged conceals the string-plate fastenings at the oblique upper edge of the same and being drawn firmly

back against the string-plate assists in holding the same in place.

My invention enables a manufacturer to make all of the string-plates uniform and to apply any desired name-plate to the string-plate at will. Further, the peculiar relative arrangement of the string and name plates, particularly the bolting of the name-plate over the string-plate, enables me to attain the result desired without destroying the impression of the conventional integral string-plate and at the same time to cause the name-plate to exert a considerable effort toward holding the string-plate properly in position.

Reference is now had to the accompanying drawings, which represent the preferred embodiment of my invention, and in which—

Figure 1 is a view of my improved string-plate standing alone. Fig. 2 is a view of the name-plate; and Fig. 3 is a front view of the upper part of the string-plate and action of an upright piano, showing my improvement in practical use and illustrating, among other things, the entire preservation of the conventional or usual appearance of such pianos.

As shown in Fig. 1, the string-plate is of the usual or conventional construction, excepting that its upper edge *a* at the right-hand side is cut downward obliquely approximately following the oblique sweep of the top row of tuning-pins at the right-hand side of the plate. The usual marginal bead at the top of the plate is broken away, as indicated at *b* and *b'*, for a distance equal to the length of such oblique edge *a*. The string-plate is provided at its oblique edge *a* with a series of screw-holes *c*, which are adapted to receive screws for assisting in holding the string-plate in position. It will be observed that these changes which I effect in the string-plate do not in any way affect the arrangement of the strings nor the assemblage of the string-plate in the piano. The string-plate is permitted to perform its usual functions unhampered and unrestrained by my invention.

The improved name-plate, as shown in Fig. 3, has an upper edge *d* and right side edge *e* at right angles to each other; but its lower edge *f* extends obliquely, sweeping from the right-hand edge *e* leftward and upward into the top edge *d* at an acute angle or point indicated at *f'*. This oblique edge *f* corresponds to the oblique edge *a* of the

string-plate, and the form of the name-plate is such that it may be arranged with the edge *f* overlapping the edge *a* and covering the screw-holes *c*, while the edges *d* and *e* of the name-plate *c* register with the top and right-hand side edges of the string-plate and give to the two elements combined—that is to say, to the improved name and string plates—the appearance of the usual string-plate in which the name of the manufacturer is cast as an integral part thereof.

The name-plate, as shown in Fig. 3, has the name of the manufacturer cast or otherwise produced thereon, and it is formed with a number, preferably three, bolt-holes *g*, which are adapted to receive the usual bolts fastened into the wooden frame of the piano.

In assembling the parts of my invention the string-plate is placed against the back or frame and secured thereto in the usual manner, excepting that the usual bolts at the upper right-hand side of the string-frame are dispensed with and screws or other fastenings are fitted in the screw-holes *c*. (Shown in Fig. 1.) The plate is strung and the various other parts of the instrument are assembled in the customary manner. After the string-plate is in position the name-plate, bearing the name of any desired dealer or other person, is placed over the upper right-hand corner of the string-plate, the oblique edge *f* of the name-plate overlapping the edge *a* of the string-plate and covering the same as well as the screw-holes and the screws fitted therein. The right and left hand extremities of the name-plate meet the marginal bead of the string-plate at the broken points *b'* and *b*, hereinbefore named, and the whole has the appearance of an integral string-plate in which the name of the manufacturer is cast. The fastening-bolts are then fitted through the openings *g*, with the result that the name-plate is not only securely drawn up into place, but the pressure of the bolts is communicated through the name-plate to the string-plate, and thus an effectual retaining effort is exerted on the string-plate. It will be seen, therefore, that by means of my invention not only am I enabled to attain the desired advantageous results incident to the use of a uniform string-plate irrespective of the name which the piano is to bear, but I cause the improved name-plate to hide the fastening-screws fitted in the openings *c* to reinforce the action of these screws and assist in holding the string-plate in position by lapsing the edge *f* of the name-plate over the edge *a* of the string-plate. As shown in Fig. 3, the bolts *g'*, which pass through the openings *g* of the name-plate, are symmetrical with the bolts *h* which are fitted in the left-hand upper edge of the string-plate, thus giving uniformity of appearance along the top of the string-plate.

In the practice of my invention a piano

manufacturer will make up the required number of string-plates uniformly of the construction shown in Fig. 2 without regard to the name which the piano is to bear. The manufacturer may, it will be observed from Fig. 3, even go to the length of completing the assemblage of the piano except for the name-plate. He may also keep in stock a number of separate name-plates, one for each of his various customers. Then upon receipt of an order for a piano of any specific name it is only necessary to apply the desired name-plate. This, it will be seen, enables the manufacturer to fill his various orders promptly without necessitating his keeping in stock a large number of string-plates differing only in name. These advantages I attain without in any way sacrificing the tone or durability of the instrument, and what is of almost equal importance without detracting from the conventional or usual appearance of the piano. This latter result is of importance, since any unusual appearance given to a well-known article of commerce, particularly such an article as a piano, necessitates explanation in all cases and in some cases might defeat the sale of the article.

Having thus described the preferred embodiment of my invention, what I claim as new with me, and desire to secure by Letters Patent of the United States, is—

1. In a piano, the combination of a string-plate, a fastening for the string-plate adjacent to its upper edge, a name-plate separate from the string-plate, the name-plate having its lower edge overlapping the string-plate at its upper edge, the name-plate covering and concealing said fastening of the string-plate and a fastening for holding the name-plate in position, the name-plate by its engagement with the string-plate assisting in holding the latter in position.

2. In a piano, the combination of a string-plate having at its upper right-hand portion an edge extending obliquely from an intermediate point at the top of the string-plate, downward and outward to the right-hand side edge thereof, said edge extending approximately parallel to the top row of tuning-pins of the string-plate and the string-plate having directly adjacent to said oblique edge a hole adapted to receive a fastening, a string-plate fastening extending through said hole, a name-plate having top and right-hand side edges at right angles to each other and having an oblique lower edge extending from the right-hand side edge leftward and upward to the top of the name-plate, the oblique edge of the name-plate matching and overlapping the oblique edge of the string-plate to hide the said fastening extending through the said hole thereof, and a fastening-bolt extending through the name-plate into the back frame of the piano, to

hold the name-plate in position and, through the name-plate, to assist in holding the string-plate in position.

3. In a piano, the combination with the frame, of a string-plate, means for securing the string-plate to the frame, a name-plate separate from the string-plate, and overlapping the string-plate at its upper edge, and means for fastening the name-plate to the

frame independently of the string-plate and for clamping the name-plate against the string-plate to assist in holding the latter in place.

WILLIAM L. BJUR.
